OTHER PUBLICATIONS

Design U.S. Appl. No. 29/450,928, filed Mar. 26, 2013, entitled Barbeque Grill by Inventor Lester Manley.

Primary Examiner — Ruth McInroy

(74) *Attorney, Agent, or Firm* — Gardner, Linn, Burkhardt & Flory, LLP

(57) **CLAIM**

The ornamental design for a barbecue grill, as shown and described.

DESCRIPTION

FIG. 1 is a front perspective view of the barbecue grill of the present invention;

FIG. 2 is a rear perspective view of the barbecue grill of FIG. 1;

FIG. 3 is a left side elevation of the barbecue grill of FIG. 1;

FIG. 4 is a right side elevation of the barbecue grill of FIG. 1

FIG. 5 is a front elevation of the barbecue grill of FIG. 1;

FIG. 6 is a rear elevation of the barbecue grill of FIG. 1;

FIG. 7 is another front perspective view of the barbecue grill of FIG. 1, shown with its left side door in an open position; and,

FIG. 8 is a rear perspective view of the barbecue grill of FIG. 7.

Top and bottom views of the barbecue grill form no part of the claimed design.

The broken lines are included for the purpose of illustrating portions of the barbecue grill that form no part of the claimed design.

1 Claim, 8 Drawing Sheets
